ABSTRACT OF THE DISCLOSURE

10

The orthodontic brace has a unitary intro-oral bow and a unitary extra-oral bow which are secured together in positive alignment without soldering, the intra-oral bow incorporating a spring portion which locks onto and adds to the spring effect of the extra-oral bow, the locking means being easily releasable to allow lateral adjustment of the extra-oral bow for unsymmetrical pressure on selected teeth when required.

20

Background of the invention

25

The present invention relates to dental equipment and specifically to a cervical traction orthodontic brace.

Most types of orthodontic braces are built up from several pieces of wire soldered together into an assembly, all adjustments being made by bending. To achieve any degree of accuracy it is necessary to use an assembly jig, unless the technician is particularly skilled. When teeth on one side must be treated differently from those on the other side, it is customary to treat each side separately or to construct a special offset brace which must be accurately made to fit. As a result the braces are usually expensive in relation to the material and structure and their somewhat limited useful life.

30

Summary of the invention

35

The orthodontic brace described herein is composed of two easily formed pieces of wire and a simple clamp element which secures the assembly in positive alignment without soldering or jigs. One piece of wire comprises an extra-oral bow by which the brace is secured to the wearer by an elastic strap or the like. The other wire element is an intra-oral bow which is attached to the teeth and has integral spring portions extending externally of the mouth and locking onto the extra-oral bow. While the clamp and the locking means together hold the assembly securely, the locking means can be manually released to allow the extra-oral bow to be manually offset laterally. This permits adjusting the brace to provide unsymmetrical pressure application without disturbing the overall alignment of the assembly.

Brief description of the drawings

45

FIGURE 1 is a perspective view, from the front, of the complete orthodontic brace;

FIGURE 2 is a front elevation view thereof;

FIGURE 3 is an enlarged sectional view taken on line 3—3 of FIGURE 2;

FIGURE 4 is a similar sectional view showing an alternate clamp structure;

FIGURE 5 is a top plan view of the brace showing offsetting of the extra-oral bow;

FIGURE 6 is a perspective view of the intra-oral bow prior to assembly;

FIGURE 7 is a side elevation view of the brace with a retaining strap; and

FIGURE 8 is a view of a biasing post which can be used to hold the strap.

Similar characters of reference indicate similar or identical elements and portions throughout the specification and throughout the views of the drawings.

2

Description of the preferred embodiments

The brace comprises an extra-oral bow 10, an intra-oral bow 12 and a clamp 14 by which the bows are secured together. Extra-oral bow 10 is a simple curved length of resilient wire, usually stainless steel or other non-corrosive wire, with a rolled eye 16 at each end for connection to a cervical retaining strap 18, as in FIGURE 7. The spacing between the eyes 16 is approximately equal to the width of the wearer's head and the strap 18 has end hook elements 20 which pass through the eyes, the strap being elastic or having some means for adjustment.

The intra-oral bow 12 is bent from a single piece of wire, preferably smaller in diameter than bow 10, and has laterally opposed, return folded spring portions 22 formed by a common upper bar 24 and lower bars 26 returning to the center parallel to the upper bar. The outer ends of the spring portions 22 are bent rearwardly to form locking loops 28 and at the center the wire ends 30 are turned rearwardly in side by side relation, as in FIGURE 6, this being the form of the intra-oral bow before assembly. Upper and lower bars 24 and 26 are generally spaced apart at a distance equal to the diameter of extra-oral bow, but the bend portions 32 where locking loops 28 turn rearwardly are closer together, so that the extra-oral bow must be forced between them.

Clamp 14 is initially a plate-like element 34 with a tubular sleeve 36 projecting from one side. The clamp is attached by threading wire ends 30 through sleeve 36 until the center of spring portions 22 are against the plate element. Extra-oral bow 10 is then inserted between upper bar 24 and lower bars 26 and the plate element 34 is folded around the grouped wires, as in FIGURE 3, to secure the assembly.

An alternative clamp 38, shown in FIGURE 4, has a separate sleeve 40 with a flanged end 42 inside the clamp, rather than being a unitary element.

When the clamp is secured the wire ends 30 are separated and bend to form bow legs 44 to fit around the teeth in the conventional manner. Spring portions 22 will be bent rearwardly by the curve of the extra-oral bow 10 and add to the effective spring pressure. The outer end portions of the extra-oral bow are snapped into the locking loops 28 and held securely therein and the brace is complete.

In normal use each bow leg 44 fits into a small tube 46 fixed on a band 48, the bow leg being provided with a fixed stop 50 to limit its penetration into the tube, as in broken line in FIGURE 7. The band 48 is secured around the tooth to be treated so that, when the strap 18 is stretched around the wearer's neck the ends of the extra-oral bow 10 are pulled rearwardly and spring pressure is applied to the selected teeth. The technique is well known and involves many different pressure, direction and alignment variations.

In the configuration shown a small biasing post 52 is inserted in each eye 16 and the strap hook elements 20 are attached to the upper end of each post by a link 54, such as an S-hook. The lower end of the biasing post 52 has an enlarged head 56, adjacent which is an annular groove 58. Resilient eye 16 fits closely in the groove 58 and holds the post securely in place. The height of the biasing post determines the amount of torque applied to the bow, since the strap attachment is offset from the plane of the bow, and different posts can be inserted according to individual requirements. In FIGURE 7 the bow legs 44 are shown inclined downwardly from the plane of the extra-oral bow, this angle being variable to control the direction of the pressure. Alternatively the hook elements 20 can be attached directly to the eyes 16 and torque applied by adjustment of legs 44 relative to the plane of the extra-oral bow 10. The pressure itself can be

controlled by bending the bow elements or adjusting the strap, although this is not usually changed to any great degree due to considerations of comfort to the wearer.

One significant feature of the brace not found in the usual soldered structures is the provision for adjustment to provide unsymmetrical pressure, for a case where more pressure is desired on one side than on the other. This is accomplished by pressing locking loops 28 back, as in the full line position in FIGURE 5, to release the extra-oral bow, which can then be pulled to one side as necessary. The clamp 14 holds the assembly securely but the extra-oral bow can be moved forcibly to have a greater length on one side, which provides a longer lever arm and consequently more pressure than the other side. When the extra-oral bow is set as required the locking loops 28 are snapped back in place, as in broken line in FIGURE 5, to lock the assembly securely. This adjustment ability avoids the necessity for building special braces at considerable expense and successive adjustments can be made as treatment progresses, to adapt to the changing configuration of the teeth.

What I claim is:

1. A cervical traction orthodontic brace, comprising:
a unitary extra-oral wire bow having end portions for connection to a cervical retaining strap;
a unitary intra-oral wire bow having rearwardly extending bowed legs for attachment to the teeth;
said intra-oral bow having opposed, laterally extending, return folded spring portions engaging said extra-oral bow;
and a clamp surrounding and frictionally securing said bows together at the central portions thereof.

2. The structure of claim 1, wherein said clamp has a rearwardly extending sleeve in which said bowed legs are held.

3. The structure of claim 1, wherein the outer ends of said spring portions have rearwardly turned locking loops in which said extra-oral bow is held.

4. The structure of claim 3, wherein each of said spring portions has an upper bar and a lower bar between which said extra-oral bow is held, the bend portions of said bars at said locking loops being spaced apart at less than the diameter of the extra-oral bow, whereby the extra-oral bow is retained in the locking loop.

5. The structure of claim 1, wherein said extra-oral bow is forcibly slidable through said clamp relative to the intra-oral bow.

6. The structure of claim 1, wherein said end portions have resilient eye elements thereof;
a biasing post frictionally held in each of said eye elements and extending substantially perpendicular to the plane of the extra-oral bow;
and means for connecting a retaining strap to the ends of said biasing posts remote from the plane of the extra-oral bow.
